UNITED STATES PATENT OFFICE.

JOHN M. DURWARD, OF BRISTOL, CONNECTICUT, ASSIGNOR TO THE BRISTOL CLOCK CASE COMPANY, OF SAME PLACE.

CLOCK-CASE.

SPECIFICATION forming part of Letters Patent No. 410,825, dated September 10, 1889.

Application filed December 27, 1888. Serial No. 294,779. (No model.)

To all whom it may concern:

Be it known that I, JOHN MURRAY DURWARD, residing at Bristol, in the county of Hartford and State of Connecticut, have invented certain new and useful Improvements 5 in Clock-Cases; and I do declare the following to be a full, clear, and exact description of the same, reference being had to the accompanying drawings which form a part of this 10 specification.

My invention relates to an improvement in cases for the class of clocks known to the trade as "French marble clocks," the object being to effect an economy of labor and material in their construction and to produce a 15 more durable article.

With these ends in view my invention consists in a sectional stone clock-case having its several parts bolted and keyed together, 20 and in certain details of construction and combinations of parts, as will be hereinafter described, and pointed out in the claims.

In the accompanying drawings, Figure 1 is a view in front elevation of a clock-case embodying my invention. Fig. 2 is a view 25 thereof in vertical longitudinal section. Fig. 3 is a detached plan view of the body or the central part of the case. Fig. 4 is a detached reverse plan view of the base of the case with one end of the base-frame in horizontal section. Fig. 5 is a view of the clock-base in vertical longitudinal section on the line *a b* of Fig. 4. Fig. 6 is an enlarged broken sectional view showing one of the bolts. Fig. 7 is a detached view, in side elevation, of one of the 30 bolts together with its nut and pin; and Fig. 8 is an enlarged broken perspective view showing one of the blind pockets *Q* in the back piece *H* of the base-frame.

My invention may be applied to the 35 construction of stone clocks, whether the material be marble, onyx, slate, or other variety of stone and whatever be the design of the case. The bolts and keys will only change in position, not in principle.

For the purposes of illustration I have herein shown my invention as applied to a clock-case made of slate finished in imitation of marble. It has a body consisting of a square 40 frame composed of four slabs *A* and of two

wings or extensions, each composed of two blocks *B* and a slab *C*. The said extensions are respectively applied to the ends of the frame, which extend an equal distance above and below them to form spaces for the transverse moldings *D*, the outer faces of which are flush with the upper and lower edges of the frame. A flat slab *E*, having its edges molded, rests upon the upper edge of the frame and upon the two upper moldings *D* and forms 55 the top of the case. The lower edge of the frame and the lower moldings rest upon a base-slab *F*, which is itself secured to an oblong base-frame composed of a front piece *G* and a similar back piece *H*, like end pieces *I I*, and binding-blocks *J J*, the latter being 60 located with the said pieces and respectively situated at the opposite ends of the base-frame, which, together with the base-slab, forms the base of the case. The base-slab *F* 65 is attached to the said blocks by bolts *K*, having their upper ends headed and their lower ends threaded to receive nuts *L*, screwed against the lower faces of the blocks.

The several pieces composing the said body 70 and base-frame are secured together by means of bolts *M* and keys *N*. For convenience I will describe the application of the bolts and keys to the construction of the base-frame, which, as illustrated in the drawings, best 75 shows them.

The inner edges of each of the binding-blocks are cut away to form three bearing-faces *O*, of which two are opposite each other, the other face being located within, between, 80 and at right angles to the said opposite faces. A hole *P* leads from each of the said faces through the adjacent parallel outer edge of the block. The base-pieces have blind pockets *Q* formed in their inner faces and located 85 so that when the parts are properly assembled they virtually form extensions of the holes *P* aforesaid. Each of these pockets *Q* is intersected at a right angle by an opening *R*, extending inward from one edge of the piece in 90 which it is formed. Bolts *M*, each threaded at one end, as at *T*, and having a perforation *U* at the other end, extend through the holes *P* in the binding-blocks and into the aligned 95 pockets *Q* in the base-pieces, in which they 100

are held by pins V, located in the intersecting openings R and extending through the holes in the bolts, the opposite ends of which are provided with nuts W, which are screwed up 5 against the bearing-faces of the blocks, whereby the base-pieces and blocks are solidly bound together. Preferably, and as herein shown, the openings R are filled in with molten metal, which sets and forms a binding 10 X for the pins, holding them in place and reinforcing the structure. One end of each of the said bolts is thus firmly embedded in a part of the case-structure.

For further binding the base-pieces together 15 their adjacent ends have vertical pockets Y and intersecting horizontal pockets Z drilled in them. These pockets are arranged so that when the base-pieces are properly assembled the horizontal pockets in one piece will communicate at an angle with the corresponding 20 horizontal pockets in the adjacent base-piece, whereby molten metal poured into one of the vertical pockets will flow through its intersecting horizontal pocket into the corresponding 25 communicating pocket, and thence into the vertical pocket by which that is intersected. When this metal sets, it forms a key N, firmly locking the ends containing it together.

If desired, wires or pins may be placed in 30 the pockets for imparting additional strength to the metallic key so formed.

The base-frame above described constitutes a composite shell, the component parts of which the binding-blocks assist in securing 35 together.

The bolts and keys employed in constructing the body of the case are the same in principle as those described, their application being only different in the shape and arrangement of the parts.

It will be readily understood from the foregoing description and from the illustrations given that these means may be applied in the construction of any sectional case without 45 regard to the design thereof.

The top, body, moldings, and base of the case are securely held together by means of two vertical rods A', having their upper ends headed and inserted into shallow pockets B', 50 formed in the lower face of the top of the case and filled with metal C' for securing the rods in place. These rods pass through holes D', formed in the upper molding D, through the spaces E' (see Fig. 3,) inclosed by the extensions of the body through holes F', formed in the lower moldings D D, and through holes G', formed in the base-slab, which, as has been explained, is secured to the base-frame. The extreme lower ends of the rods are threaded 55 to receive nuts H', which are screwed against the lower face of the slab, whereby the said top, moldings, body, and base are firmly held together.

The projecting lower ends of the bolts K 60 are employed for securing in place the sounding-board I', as shown by Fig. 2 of the

drawings. This sounding-board carries the gong (not shown) of the clock.

The body and base of the clock-case form, as it were, compound transverse case-sections, 70 and the top and base slabs and the moldings simple transverse case-sections, such simple and compound sections being held together by vertical bolts.

By making a clock-case as described a very 75 fine case is secured without the use of the amount of material required for this class of cases as ordinarily constructed by binding the parts together by overlapping and cementing them, whereby economy of material 80 and labor is secured. The several parts of the case being positively secured together by bolts and keys, the case is very durable and will not come to pieces under the action of moisture and heat, whereas cases made in the 85 old way, with cement and pitch, are always coming to pieces. Being lighter than the ordinary stone clock-case, they are easier to handle and less expensive to transport. Furthermore, the parts being held together by 90 bolts and metallic keys are so solid in their relations one to another that the case has virtually the property of a single piece of stone and gives a fine effect to the bell or gong with which it may be supplied.

It is apparent that in carrying out my invention some changes from the particular forms herein shown and described may be made. I would therefore have it understood that I do not limit myself to such forms, but hold myself at liberty to make such changes and alterations as fairly fall within the spirit and scope of my invention.

Having fully described my invention, what I claim as new, and desire to secure by Letters Patent, is—

1. In a sectional stone clock-case, the combination, with a section provided with a blind pocket formed in its inner face and with an opening intersecting the said pocket at an angle, of a bolt having one end perforated and inserted into the said blind pocket and a pin located in the said opening and passing through the perforation in the bolt, substantially as set forth.

2. In a sectional stone clock-case, the combination, with a stone section provided with a blind pocket formed in its inner face and with an opening intersecting the said pocket at an angle, of a bolt having one end perforated and inserted into the blind pocket, a pin located in the said opening and passing through the perforation in the bolt, and a filling located in the opening and keying the pin in place, substantially as set forth.

3. In a base for a stone clock-case, the combination, with a front piece, a back piece, and two end pieces, of two binding-blocks located within and at opposite ends of the shell formed by the said pieces, and each having its inner 130 face cut away to form three bearing-faces, and three bolts carried by each block, having

their inner ends embedded and pinned in the respective adjacent base - pieces and their outer ends provided with nuts screwed against the bearing-faces of the block carrying them, 5 substantially as set forth.

4. A sectional stone clock-case having its several parts keyed together by metallic keys, consisting of binders angling to each other and formed by pouring molten metal into 10 pockets formed in adjacent parts of the case, so as to communicate with each other in angles when such parts are properly assembled, substantially as set forth.

5. A stone clock-case having two of its parts 15 each provided with intersecting vertical and

horizontal pockets arranged so that when the parts are properly assembled their corresponding horizontal pockets will communicate, so as to permit the formation of a key, binding the two parts together, by pouring metal into 20 the vertical pockets of one of them, substantially as set forth.

In testimony whereof I have signed this specification in the presence of two subscribing witnesses.

JNO. M. DURWARD.
